UNITED STATES PATENT OFFICE.

NATHAN M. LOWER AND ALBERT R. CHALKER, OF PITTSBURGH, PENNSYLVANIA, ASSIGNORS TO LOCOMOTIVE STOKER COMPANY, A CORPORATION OF PENNSYLVANIA.

DISTRIBUTOR TUBE FOR STOKERS.

Application filed March 18, 1922. Serial No. 543,829.

The invention relates to the distributor tube or nozzle through which coal is discharged into a fire box and is particularly adapted for use and is illustrated in connection with a stoker mechanism of the type forming the subject matter of Letters Patent No. 1,371,252 granted to Nathan M. Lower March 15, 1921. As the invention appertains to the distributor, only so much of the remainder of the stoker mechanism is shown as is necessary to indicate the relation of the parts. As the distributor tubes used in connection with the stokers of the type shown in the Lower patent project into the fire box they are subjected to intense heat and are consequently short-lived.

One of the objects of this invention is to provide a construction in which the parts of the distributor which are in danger of being burned off are removable, thus reducing the cost of replacement. A further object of the invention is to provide means for cooling the exposed parts, and thus lengthening their term of service, and a still further object is to provide an improved form of baffle or abutment for arresting a portion of the impelled fuel and delivering it to the back end of the fire-box.

The invention consists of a structure such as is hereinafter described and is illustrated in the accompanying drawings, in which

Fig. 1 is a detail vertical section through the back head of a locomotive fire-box, showing the improved distributor tube applied thereto, a fragment of the adjacent portions of the stoker mechanism being shown in elevation;

Fig. 2 is a transverse section of the distributor tube on the line 2—2 of Fig. 1;

Fig. 3 is a similar view on the line 3—3 of Fig. 1;

Fig. 4 is a sectional detail on the line 4—4 of Fig. 1;

Fig. 5 is a plan view of the distributor;

Fig. 6 is a central plan section of the distributor and of the portion of the stoker to which it is attached;

Fig. 7 is a central vertical longitudinal section of the distributor showing a modified form of construction; and

Fig. 8 is a bottom plan view thereof.

The stokers for use with which the improved distributor tube is especially adapted have heretofore been used in connection with locomotives. There is shown at 10 a

portion of the back head of a boiler having an aperture within which is fitted a sleeve 11. A fragment of the stoker head is shown at 12 which in practice is known as the elbow. The distributor tube 13 is fitted to the stoker elbow 12 and is secured thereto by means of a hook bolt 14 and projects through the sleeve.

The inner end of the tube 13 terminates substantially in the plane of the inner face 65 of the back head 10. A deflector plate 15 projects forwardly over the top of the tube and is removably secured thereto, being provided with a stem 16 having a socket for fitting upon an upwardly projecting lug 70 on the top of the tube, the inner end of the stem 16 engaging under a lip 18 formed on the tube. As shown in Fig. 5 the deflector plate 15 is relatively wide at its forward end and is reduced at its rear end to form the 75 socket engaging stem 16. In order to strengthen the plate and prevent its outer end from bending downward under its weight and the intense heat of the firebox, the upper side of the plate 15 is provided 80 with a reinforcing rib 150.

The bottom of the tube 13 is open and a plate 19 fits within this opening, resting upon a bridge 20 integral with the side walls 85 of the tube, and extending across its opening and having a pair of lugs 21 which engage in recesses in the margins of the tube walls thereby interlocking the plate with the tube walls and preventing its accidental displacement. The tube 13 is also provided 90 with a bridge 22 at its rearward end connecting the margins of its side walls and the rear end of the plate 19 rests thereupon.

A stem 23 projects forwardly from the body of the plate 19 of which it constitutes 95 an integral part and at the forward end of this stem there is carried a cross bar 24, the length of which is substantially equal to the width of the plate 19. The inner face of this bar is preferably flat and projects somewhat above the plane of the upper surface of the plate 19, forming an abutment for arresting the lower stratum of coal impelled 100 through the tube.

The stem 23 and abutment 24 are cored to form a continuous passage therethrough, as indicated at 25, 26, the passage 26 extending longitudinally through the abutment and being open at the ends thereof.

At 27 there is shown the usual nipple 110

extending through the floor of the elbow 12 and having a series of jet openings 28 directed through the tube, the nipple 27 being adapted for the attachment thereto at its 5 lower end of a steam pipe. A pipe or nipple 29 leads laterally from the nipple 27, below its jet openings, and terminates adjacent the rear end of the passage 25 through the stem 23, into which it discharges. The rear end 10 of the stem 23 is flared, as indicated at 30, to permit the entry of air induced by the steam blast from the nipple 29. The air and steam passing through the passages 25 and 26 will tend to prevent the abutment and its 15 supporting stem from becoming overheated, thus prolonging the life of the same.

The bridge 22 is channeled transversely, as shown at 31, to loosely receive the pipe or nipple 29.

20 Inasmuch as the tube and its bottom are not exposed to the intense heat of the furnace it may be found desirable to form the bottom of the tube as an integral part thereof, providing only for the removal of the 25 abutment.

This form of construction is illustrated in Figs. 7 and 8, the bottom 32 of the tube 13 being formed integral with its side walls. The abutment 24 is of the same form as 30 shown in Fig. 1, but its stem 33 is not made integral with the bottom of the tube but is provided with a pair of lateral shoulders 34, 35, adapted to rest upon a pair of lips 36, 37, formed on the bottom of the tube. The 35 stem 33 is also provided at its rearward end with a pair of lateral lugs 38, 39, which engage back of a pair of lugs 40, 41, formed on the bottom of the tube, and thus prevent the withdrawal of the stem. A second pair 40 of lugs 42, 43, formed on the bottom of the tube, prevent the stem from being shoved in too far. In order to permit the pipe 29 to extend well into the passage 25 and yet provide for the assembling of the parts, the 45 upper wall of the stem 33 may be slotted at its rearward end indicated at 44.

In the operation of the device the fuel is discharged into the tube 13 from the elbow 12 and is projected forwardly through the 50 tube by the steam issuing from the jet openings 28 and is scattered through the tube, some of it being thrown upwardly against the plate 15 which deflects it downwardly and scatters it over the central zone of the 55 fire box, the plate 15 preventing the fuel from being thrown upwardly and into the boiler tubes; some of the fuel strikes the side walls of the tube and is thereby prevented from being too widely scattered; some of it 60 is projected forwardly through the tube without encountering any of its walls and is carried well to the front end of the fire box; and some of it is directed laterally to the sides of the fire box, especially those portions 65 that come in contact with the steam

and air issuing from the passage 26. The lower stratum of the fuel follows the bottom of the tube and encountering the upstanding abutment 24 is arrested and dropped upon the rearward end of the grate. Lumps of 70 coal in the lower stratum which strike the abutment 24 below their centers of gravity bound over the abutment and fall upon the grate a little in front of it.

When under the influence of the intense 75 heat of the furnace the abutment or its stem or the plate 15 become burned away or warped, they may be readily replaced without detaching the tube 13 from the elbow 12. This detachability of the parts not only 80 reduces the cost of replacement, but permits the interchange of parts with the minimum expenditure of labor or delay to permit the entire cooling of the fire box.

While a preferred form of construction 85 is shown and described, various changes of detail may be made without departing from the scope of the invention.

We claim as our invention:

1. A tubular fuel distributor for stokers 90 having a removable bottom, an abutment extending transversely to the forward end of the tube and extending above the plane of the bottom and being spaced forward from the front end thereof, and a stem connecting the abutment with the bottom.

2. A tubular fuel distributor for stokers having a removable bottom, an abutment extending transversely to the forward end of the tube and extending above the plane of 100 the bottom and being spaced forward from the front end thereof, and a stem connecting the abutment with the bottom, such stem and abutment having a continuous passage therethrough, and a pipe discharging into 105 the rearward end of the passage.

3. A distributor tube for stokers having an open bottom and a bridge crossing the opening, a plate fitting within the opening and resting on the bridge and having its 110 rear end engaging said distributor tube, an abutment transverse to the length of the plate and spaced from the forward end thereof, and a stem connecting the plate and abutment, such stem and abutment having 115 a continuous passage therethrough, and a pipe discharging into such passage.

4. A distributing member including a plate adapted to form the bottom of a tubular distributor for a stoker, means on the plate to interlock with the distributor, a stem projecting forwardly from the end of the plate and a fuel abutment on the stem spaced from the front end of the plate and 120 extending above the upper surface of the plate.

5. A distributing member including a plate adapted to form the bottom of a distributor tube for stokers, and having means 125 for interlocking engagement therewith, a 130

fuel abutment spaced forwardly from the front end of the plate and extending above its upper surface and a narrow stem connecting the bar with the plate.

5 6. A distributor for stokers including a tube open at the bottom, a bridge extending across the open bottom, a plate resting on the bridge and interlocked with the tube, a fuel abutment in front of the plate and 10 extending above its upper surface.

15 7. A distributor for stokers including a tube open at the bottom, a bridge connecting the side walls of the tube at the bottom, a plate resting on the bridge and having lugs interlocked with the side walls and a fuel abutment in front of the plate and extending above its upper surface.

20 8. In a distributor for stokers, a tubular member adapted to be approximately horizontally positioned in service, and having an open bottom and means at its upper side adapted to interlock with a removable deflector, and a bridge crossing its open bottom adapted to support a removable bottom plate.

25 9. In a distributor for stokers, a tubular member adapted to be approximately horizontally positioned in service including a top having means adapted to interlock with a removable deflector, side walls connected with the top and a bridge connecting the side walls adjacent to their lower edges and adapted to support a removable bottom plate, the bottom of the tube being open except for said bridge.

30 10. In a mechanical stoker, the combination of a substantially horizontal tube flattened at the bottom, a stem extending forwardly from the bottom of the tube and a fuel abutment in the form of a cross bar carried by the stem spaced forwardly from and projecting above the bottom of the

tube, the space between the cross bar and the bottom of the tube being open for coal to pass downwardly on each side of the 45 stem.

11. In a mechanical stoker, the combination of a substantially horizontal tube having a flattened detachable bottom, a jet for impelling coal through the tube, a stem integral with and projecting forwardly from the flattened bottom and a fuel abutment in the form of a cross bar carried by the stem, spaced from the forward end of and extending above the bottom, the space between the 50 55 cross bar and the front end of the bottom being open for coal to pass downwardly on each side of the stem.

12. A fuel deflector member for use on the upper side of a distributor tube having 60 a socket and a projecting lug thereon, comprising a plate reduced in width at one end to engage said socket, and provided with a socket for receiving said lug, the width of the forward portion of said plate being not 65 less than the internal diameter of said tube, said plate being provided with a reinforcing rib on its upper surface for preventing bending of said plate when the same becomes heated while in use. 70

13. A fuel distributing member comprising a plate adapted to form the bottom of a distributor tube for stokers, said plate terminating adjacent to the forward end of said tube when in position therein, and having 75 means for interlocking engagement therewith, a fuel deflecting abutment spaced forwardly from the front end of the plate and extending above its upper surface, and means for connecting the abutment with the 80 plate.

NATHAN M. LOWER.
ALBERT R. CHALKER.

- fuel abutment spaced forwardly from the tube, the space between the cross bar and the front end of the plate and extending above its upper surface and a narrow stem connecting the bar with the plate.
6. A distributor for stokers including a tube open at the bottom, a bridge extending across the open bottom, a plate resting on the bridge and interlocked with the tube, a fuel abutment in front of the plate and extending above its upper surface.
7. A distributor for stokers including a tube open at the bottom, a bridge connecting the side walls of the tube at the bottom, a plate resting on the bridge and having lugs interlocked with the side walls and a fuel abutment in front of the plate and extending above its upper surface.
8. In a distributor for stokers, a tubular member adapted to be approximately horizontally positioned in service, and having an open bottom and means at its upper side adapted to interlock with a removable deflector, and a bridge crossing its open bottom adapted to support a removable bottom plate.
9. In a distributor for stokers, a tubular member adapted to be approximately horizontally positioned in service including a top having means adapted to interlock with a removable deflector, side walls connected with the top and a bridge connecting the side walls adjacent to their lower edges and adapted to support a removable bottom plate, the bottom of the tube being open except for said bridge.
10. In a mechanical stoker, the combination of a substantially horizontal tube flattened at the bottom, a stem extending forwardly from the bottom of the tube and a fuel abutment in the form of a cross bar carried by the stem spaced forwardly from and projecting above the bottom of the
11. In a mechanical stoker, the combination of a substantially horizontal tube having a flattened detachable bottom, a jet for impelling coal through the tube, a stem integral with and projecting forwardly from the flattened bottom and a fuel abutment in the form of a cross bar carried by the stem, spaced from the forward end of and extending above the bottom, the space between the cross bar and the front end of the bottom being open for coal to pass downwardly on each side of the stem.
12. A fuel deflector member for use on the upper side of a distributor tube having a socket and a projecting lug thereon, comprising a plate reduced in width at one end to engage said socket, and provided with a socket for receiving said lug, the width of the forward portion of said plate being not less than the internal diameter of said tube, said plate being provided with a reinforcing rib on its upper surface for preventing bending of said plate when the same becomes heated while in use.
13. A fuel distributing member comprising a plate adapted to form the bottom of a distributor tube for stokers, said plate terminating adjacent to the forward end of said tube when in position therein, and having means for interlocking engagement therewith, a fuel deflecting abutment spaced forwardly from the front end of the plate and extending above its upper surface, and means for connecting the abutment with the plate.
